CYRUS A. BRYANT, OF PASSAIC, NEW JERSEY

TOOL

Application filed March 19, 1928. Serial No. 262,788.

My invention relates to improvements in tools and particularly to that class of tools in which a two-member handle is acted upon by a spring to press apart the members.

An object of my invention is to provide a simple and convenient means for spreading the members forming the handle of a tool, a further object of my invention is to provide spring means for locking the members of a handle in closed relation, a further object of my invention is to provide simple and convenient spring means for facilitating the operation of a tool and for locking the members of a tool handle comprising plural parts.

I accomplish these objects by the device illustrated in the accompanying drawings, in which

Figure 1 is a view of a tool closed, with the spring shown in dotted lines in locked position.

Figure 2 is a view of the same open and with the parts shown in dotted lines at maximum expansion, and

Figure 3 is a detail of the spring.

Similar characters refer to similar parts throughout the several views.

My invention may be advantageously employed in tools of various kinds as well as in various other mechanical devices in which it is desired to spread or fasten in fixed relation

two or more separable members.

The drawings are for illustration only and are not intended to limit the invention.

I have shown in the drawings a tool embodying my invention, in which two pivotally connected handled members 1 and 2 constitute the handle and are fulcrumed at 3 whereby they may be spread or brought together as desired.

On the member 1, I provide a curved leaf spring 4, the free end section 5 of which normally bears against and presses upon the inner face 2¹ of the member 2, whereby the free ends of the handle members 1 and 2 are normally pressed apart to an open position.

The spring 4 is secured at its base 11, to the member 1, adjacent the fulcrum 3, by means of a rivet 6 or in any other desired manner and is preferably countersunk in the member 1 in such manner as not to interfere with the operation and closing of the handle sections.

Adjacent the free end 5 of the spring 4, I provide a cut out seat, which may be in the form of an elongated slot 7, adapted to be engaged by the lugs 8 and 9 respectively, on the handle member 2, as hereinafter described.

The device being thus assembled, the free end section 5 of the spring 4 will normally bear against the inner face 2¹ of the handle member 2 and thus tend to spread apart the free ends of the handle members 1 and 2 toward the position shown by the dotted lines in Figure 2.

In use, the separable handle members 1 and 2 are grasped by the hand of the operator and pressed together manually by force exerted against the pressure of the spring 4 which normally tends to spread the handle members 1 and 2 apart as the pressure by the hand of the operator is reduced, and the free end section 5 of the spring 4 will thus slide upon the face 2¹ of the member 2 as the handle opens and closes.

I provide on the handle member 2 a lug 9 so positioned as to detachably engage the slot 7 in the free end 5 of the spring 4 when the handle members 1 and 2 reach the predetermined point of desired maximum normal spread.

A lug 8 is positioned on the handle member 2 at a point beyond that reached by the seat 7 of the spring 4 at the extreme point of travel along the handle member 2 toward its free end, in the course of operation as above described, so that the lug 8 will not be normally engaged by the slot or seat 7. The lug 8 preferably has an inclined face on its side toward the approach of the spring 4 so

that the spring 4 will be the more easily carried up over the lug 8 as it approaches the point of engagement.

In operation, the spring 4 will thus constantly tend to spread apart the free ends of the handle members 1 and 2 in operation, the spread being limited at the point of desired maximum expansion by the lug 9 and seat 7, it being however, possible to permit further expansion of the members 1 and 2 by releasing the seat 7 from engagement with the lug 9, which may be done by lifting the free end of the spring 4 so that the slot 7 is released from engagement with the lug 9, when the spring 4 will be free to exert further its pressure against the handle member 2 and spread the handle members as shown by the dotted lines in Figure 2 to their maximum spread, limited only by the expansion of the spring 20 and the form and construction of the tool. The lug 9 is provided with an inclined face 9¹ on the side approached by the spring in its travel from maximum expansion to the normal operative position and with a vertical face on the side approached by the spring in its travel from its compressed position whereby the lug 9 is operative to limit the spread of the handle members but does not prevent them from being pressed together.

When it is desired to lock the handle members 1 and 2 in closed relation, the handle members are brought together to the position of maximum compression, at which position the slot 7 of the spring 4 will lie short of the point of engagement with the lug 8 and pressure is then exerted against the convex side of the spring 4 reducing the bend of the spring 4, as shown by dotted lines in Figure 1, thereby extending the end section 5 of the spring 4 until its slot or seat 7 reaches and engages the lug 8. The tension of the spring 4 will thus hold or lock the handle members 1 and 2 in closed relation.

I find it desirable to so construct the device that the pivot or fulcrum 3, the base 11 of the spring 4 and the lug 8 will be in approximately the same lineal plane when the handle members are at the position of maximum compression. The spring 4 is of such length and form that when in locked position the bend intermediate the ends of the spring 4 will provide sufficient slack so that the spring may be extended sufficiently to permit the seat 7 of the spring 4 to be released from its engagement with the lug 8 whereby the handle members may be unlocked for operative use. As will thus be observed, the spring 4 performs the double function of spreading the handle members in operative use and also locking the handle members in closed relation, as desired.

Having thus described my invention, what I claim is:

1. In a device of the character described, the combination of a pair of pivotally con-

nected handled members, a spring fixed to one of said members adjacent the pivotal connection and having a free end adapted to bear against the other said member and adapted to freely slide thereon when the handles swing on their pivotal connection, a seat in the free end of said spring, and engaging means on said other member adapted to engage said seat in the spring when the spring is extended beyond the point of maximum normal travel.

2. In a device of the character described, the combination of a pair of pivotally connected handle members, spring means fixed to one of said handle members and having a free end, engaging means on the other said handle member positioned beyond the field of normal travel of the spring and adapted to engage said spring adjacent its free end when the spring is extended beyond its normal maximum travel.

3. In a device of the character described, the combination of a pair of separable handle members, spring means therebetween and adapted to normally spread said handle members, engaging means on said handle members adapted to engage the spring means to limit the expansion of the handle members and other engaging means on said handle members adapted to engage said spring means to lock the handle members in closed relation.

4. In a device of the character described the combination of a pair of crossed handle members, a pivotal connection therefor, spring means adapted to spread said handle members, lugs on said handle members adapted to engage said spring means, said spring means being adapted to be extended at the position of maximum operative compression whereby one of said lugs may be engaged to lock the handle members in closed relation.

5. In a device of the character described, the combination of a pair of pivotally connected handled members, spring means capable of expansion secured to one of said handled members adjacent the pivotal connection and having a free end adapted to bear against the other said handled member, spaced lugs on the other said handled member positioned to permit said free end of the spring means to freely slide between said lugs, one of said lugs being adapted to engage said spring means to limit the spread of the handles and the other said lug being positioned to engage said spring means beyond the point of normal maximum expansion to lock the handles.

6. In a device of the character described, the combination of a pair of pivotally connected handle members, spring means secured to one of said handle members adjacent the pivotal connection and adapted to bear against the inner face of the other said handle member and to travel thereon, a pair of spaced lugs on the other said handle mem-

ber, said lugs having inclined faces in the direction of the pivotal connection and having substantially vertical faces on their opposite sides to permit the travel of the spring
5 means freely in the direction of the free end of the said handle and to restrict the inward travel of said spring means, one of said lugs being positioned beyond the normal field of travel of said spring means and being engaged thereby to lock said handle members in closed relation when said spring is extended.

10 In testimony whereof, I have signed my name to this specification this twelfth day of March, 1928.
